UNITED STATES PATENT OFFICE

2,419,670

SHOE HEEL

John H. Buechler, Chicago, Ill.

Application April 3, 1946, Serial No. 659,320

3 Claims. (Cl. 36—39)

1

My invention relates to an improvement in a shoe heel of rubber, leather, or any material that can be used for a shoe heel, and the object of my improvement is to provide an invertible, as well as rotating, wearing part of a heel to afford longer wear before replacing with new heels. I attain this object by means illustrated in the following drawings, in which:

Fig. 1 is a perspective view of the entire heel assembly.

Fig. 2 is a perspective view of a cup-shaped pilot.

Fig. 3 is a sectional view through the diameter 3—3 of the invertible ring. In this drawing a rubber ring is used.

Fig. 4 is a sectional view through 4—4 in Fig. 1.

In Fig. 1 the invertible ring is indicated by 11, the cup-shaped pilot with its open end adjacent to and secured to the shoe is shown by 12, the stationary part of a shoe heel by 14, and 13 indicates the remaining part of the heel that completes the shape of an ordinary rubber heel. As said before other heel material can be used instead of rubber for this invertible ring.

In Fig. 2 the wall of the pilot is indicated by 15, the height of which does not exceed the thickness of the invertible ring 11, this wall having pairs of parallel circumferential slits 16 which converge to form an angle at one end of a tongue 17. These slits 16 are to be positioned so that the distance from the tip of the angle 18 to the open end of the pilot 12, is less than one half of the thickness of the invertible ring 11, the reason for which will be given later in this specification. This free end of the tongue 17 is bent to form the angular fin 18 projecting outwardly and radially. This cup pilot 12 is made of thin spring steel or other resilient material so that fins 18 will yield inwardly by a slight pressure and come back again when the pressure is removed, the purpose of which will be revealed later in this specification. This illustrates one of the obviously different ways to form a yielding projection from the wall of a pilot attached to a shoe.

In Fig. 3 number 19 is a sleeve, or lining, of metal or other firm material inside the hole of the rubber ring, and 20 is an inside circumferential angular groove formed midway of the length of said sleeve to receive the fin or projection 18 which has a similarly angular contour. Number 21 is an outside flange formed on the sleeve midway of its length, 22 is the flange of rubber which is vulcanized, or otherwise mechanically held to the sleeve 19 and flange 21. Other materials of course can be used instead of rubber.

5 In Fig. 4 the sectional view through 4—4 of ring 11 shows the angular projection 18 in the similarly angular ring groove 20 resting on the side of the groove which happens to be nearest to the shoe heel 14. 24 is a nail holding the pilot 12 to the shoe heel 14.

10 When the invertible ring 11 and the rear edge of a shoe heel 14 are placed together so that the radii of both coincide and the pilot 12 placed into the ring hole with the open end adjacent to the shoe heel 14 and nailed through the hole 23, or otherwise secured to the shoe heel, and part 13 is also secured to the shoe heel, the assembly is complete.

15 To invert or rotate, the ring 11 can be removed with the aid of a thin blade or kitchen knife to pry the ring from the shoe. To replace, after inverting or rotating ring 11, it can be forced over the already stationary pilot 12, causing the fins 20 to yield inwardly until the groove 20 permits the fins 18 to snap back out into said groove 20. It will be necessary to eliminate the sleeve 19 and the flange 21 if the pilot is formed with an unyielding projection.

20 25 An important feature of this invention is the fact that the projecting angle of fin or projection 18 is nearer to the shoe heel 14 than the similar contour of the groove angle 20. Due to this difference, it will be clearly seen that the fin or projection angle 18 will rest on the one side of the groove 20 that is nearest the shoe heel 14, thereby holding the ring 11 firmly to the shoe heel 14.

When the entire edge of one face of the aforesaid ring 11 is partly or completely worn off, and 30 35 the ring 11 is inverted and again placed over the already positioned pilot 12, the sleeve 19 and flange 21 will sustain the unworn face of the ring flange 22 to the level of a new heel as no part of the ring flange 22 can sag beyond the sleeve flange 21.

40 45 The flanged sleeve 19 and 21 with its angular groove 20 as shown in Fig. 3 can be made of two stampings and the flanges spot welded together, or otherwise held, if desired. The pilot Fig. 2 can be a drawn and stamping job before tempering. When using an angularly grooved rubber ring without the sleeve 19 and the flange 21, it will not be necessary for the similarly angular projection from the wall of the pilot to be formed of 50 yielding material. Thus, the complete assembly can be made at a reasonable cost to the user, and besides; each of the two sides of this invertible heel affords four wearing segments, thus supplying eight times the wear of an ordinary shoe heel.

55 In view of the foregoing specification, I claim:

1. A ring shaped heel having an angular groove formed circumferentially midway in its inner wall and adapted to receive a similarly angular projection or projections formed outside on the wall of a pilot attached to a shoe.

2. A heel as set forth in claim 1 in which said inner wall is provided with a lining or sleeve of firm material.

3. A heel as set forth in claim 1 in which said inner wall is provided with a lining or sleeve of firm material and said lining or sleeve has an external flange midway of its length.

JOHN H. BUECHLER.
